Nº 26.

UNITED STATES PATENT OFFICE.

HERMAN GRIEBEL, OF CHICAGO, ILLINOIS, ASSIGNOR TO THEODORE A. KOCHS, OF SAME PLACE.

DESIGN FOR A SHAVING-MUG.

SPECIFICATION forming part of Design No. 13,403, dated November 14, 1882.

Application filed October 13, 1882. Term of patent 3½ years.

To all whom it may concern:

Be it known that I, HERMAN GRIEBEL, a citizen of the United States, residing at Chicago, in the county of Cook and State of Illinois, have invented and produced a new and original Design for Shaving-Mugs, of which the following is a specification, reference being had to the accompanying drawings, and to the letters of reference marked thereon, which to form a part of this specification.

The engraving shows a shaving-mug having my design.

The leading features of my design are a knotted ribbon, two branches of leaves passed vertically through such knot, with their upper ends curved in opposite directions, and two tulip-shaped cups extending from the sides of such knot, out of which grow branches of forget-me-not flowers.

A is the shaving mug, which is of the usual shape, of white porcelain, with a tinted white border around its upper portions and gilded stripes around its upper and lower rims and around the lower edge of the tinted border.

Upon the face of this cup is painted a red ribbon, *a*, that is knotted to form an upward

double loop, and has pending ends. Two branches of leaves, *b*, are shown as passed vertically through such knot, with their upper ends curved in opposite directions. Talip-shaped gilded cups *c* are represented as being tied with their stems in the knot of the ribbon and extending sidewise in a downward curve, and two branches, *d*, of forget-me-not flowers extend from the cups *c* at each side to 35 the handle *e*.

What I claim is—

The design for a shaving-mug, herein shown and described, the same consisting in the painting of a looped and knotted ribbon, *a*, of two 40 branches of leaves, *b*, of the tulip-shaped cups *c*, and of the branches of forget-me-not flowers *d*, all arranged substantially as described and shown.

In testimony that I claim the foregoing as 45 my design I affix my signature in presence of two witnesses.

HERMAN GRIEBEL.
